United States Patent Office.

JAMES T. CLARK AND JOHN D. BESLER, OF GALESBURG, ILLINOIS.

Letters Patent No. 80,601, dated August 4, 1868.

IMPROVEMENT IN SWITCHES.

The Schedule referred to in these Letters Patent and making part of the same.

TO ALL WHOM IT MAY CONCERN:

Be it known that we, JAMES T. CLARK and JOHN D. BESLER, both of Galesburg, in the county of Knox, and State of Illinois, have invented a new and useful "Treble-Safety Railroad-Switch;" and we do hereby declare that the following is a full and exact description thereof, reference being had to the accompanying drawings, making part of our specification, in which—

Figure 1 represents the position of the rails and switches adjusted for the main track.

Figure 2, the same, adjusted for the right track, and

Figure 3 the same, adjusted for the left track.

The nature of our invention consists in the combination of two short and two long pointed movable rails with two stationary rails, so arranged that it forms a treble-safety railroad-switch, as will be hereinafter fully explained.

To enable others skilled in the art to make and use our invention, we will proceed to describe its construction and operation.

A is a point, to which come three different railroad-tracks, B B', C C', and D D', C C' being the main track. The ends of the outside rails, B and D', of these tracks connect with the ends of the two stationary rails E E', extending from the point A to the point F, where they meet the rails T T' of the regular track; Inside of the stationary rails E E', at the point A, are attached to the tie, in a usual way, four movable pointed rails, consisting of two pairs, of different lengths, the rails G G' of the shortest pair being placed opposite the rails C and B', and the rails H H', of the longest pair, opposite the rails D and C', each pair being moved independently by connecting-rods m n and target-levers M N, which are supposed to be worked by one man. We make the short movable pointed rails about fourteen, and the long ones about twenty-four feet long, but this length may vary more or less, according to circumstances.

The operation consists in this, that for the main track C C', the switches are moved in opposite directions, the short switch G G' being switched to the stationary rail E, and the long switch H H' to the stationary rail E', as represented on fig. 1.

For other tracks, both switches are moved in the same direction, viz, for the track B B' they are moved to the rail E', as on fig. 2, and for the track D D' they are moved to the rail E, as on fig. 3.

The advantages of our treble-switch over the common treble stub-rail switch now in use, are obvious. There, if a movable bar is not in its proper place, the train, by leaving the depot, where most of the accidents happen, will run off the track, while in our arrangement, if a switch is not properly placed, the flanges of the car-wheels, entering gradually and wedge-like into the spaces between the stationary and the pointed rails, will set the switches to their proper places, and although they will bend the connecting-rods and the target-levers of the switches, will never run off the track.

We are aware that a switch has heretofore been made having one pair of movable rails, and therefore we do not claim such; but, having described our invention,

What we claim as our invention, and desire to secure by Letters Patent, is—

The combination of the two short, G G', and two long, H H', pointed movable rails with two stationary rails E E', forming a treble-safety switch, the whole arranged and operating substantially as and in the manner herein described and specified.

J. T. CLARK,
J. D. BESLER.
